FIG. 4.

UNITED STATES PATENT OFFICE

2,491,717

METAL FORMING MACHINE

Russell Creighton, Kenmore, N. Y., assignor to
General Riveters, Inc., Buffalo, N. Y.

Application May 24, 1945, Serial No. 595,595

6 Claims. (Cl. 153—21)

1

This invention relates to metal forming machines and particularly to machines wherein sheets of metal or similar material are permanently deformed by the application of pressure and heat.

In fabricating sheet metal it is frequently desired to use countersunk rivets, and for this reason it is common to form beveled depressions in metal sheets around and concentric with pre-formed rivet holes to accommodate countersunk heads. This operation is commonly known in the art as "dimpling" and is conventionally done as a cold die operation. In the case of certain alloys, however, for instance high tensile strength aluminum alloys, conventional cold dimpling cannot be accomplished because of unusual behavior and characteristics of the particular alloys.

I have found that a proper degree of local heating of the work piece makes it possible to form permanent and wholly satisfactory countersink formations or "dimples," in these hitherto troublesome metals and the present application discloses apparatus and a mode of operation for attaining the desired results in a commercially workable manner.

The accompanying drawings show one specific form of apparatus by way of example and a complete description thereof is set forth in the following specification, which likewise sets forth full details as to time and temperature ranges suitable for dealing with high tensile strength aluminum alloys; however, it is to be understood that the apparatus may be variously modified and the temperatures and times employed will vary with the particular alloy being dealt with. The principles of the present invention are not limited to the specific example included herein but are to be measured only as defined in the appended claims. For one thing, reference is had above to preformed rivet holes, but if any other considerations should so dictate, the dimpling may precede the forming of the rivet hole without affecting the principles set forth herein.

The high tensile strength aluminum alloys mentioned in the foregoing are well known to those skilled in air frame fabricating and analogous arts. For instance, the Aluminum Company of America designates its high tensile aluminum alloy 75S, that of Reynolds Metals is designated No. 301, and that of Ryan Aeronautical Corporation is called T81. The same apparatus and principles may be employed in dealing with other alloys of similar behavior characteristics with respect to present considerations, for instance, magnesium alloy sheets.

2

In the drawing.

Fig. 1 is a side elevational view of one form of apparatus for practicing the present invention with portions of the casing broken away for added clearness;

Fig. 2 is a fragmentary top plan view of the apparatus of Fig. 1 with the casing or framework in cross section;

Fig. 3 is a fragmentary view taken similarly to Fig. 1 but showing only the upper portion of the apparatus with the casing or framework likewise in cross section; and

Fig. 4 is a cross sectional view taken in a vertical plane on an enlarged scale through the punch and die mechanism per se.

Throughout the several figures of the drawings, like characters of reference denote like parts and the numeral 10 designates generally a press framework or casing including a hollow upright pedestal portion 11 having a laterally projecting hollow base 12 and a head portion 13 likewise projecting laterally therefrom to form a work receiving gap between the base and the head portion. In the form shown, the base 12 has rigidly secured thereto a U-shaped element 13 which serves as a horn and supports a lower die means 14, which will presently be described in further detail.

An upper die is designated generally 15 in Fig. 30 and is secured to an upper ram 16 which has bearing in the headed portion 13 of the frame for vertical reciprocation. An air cylinder 17 is provided with an operating piston 18 which is fixed to the upper ram 16 in any convenient manner.

The upper and lower dies are shown in detail in vertical cross section in Fig. 4 and reference will now be had thereto. The lower die, which has been designated generally 14, comprises a central male die element 22, whose lower end 23 is provided with a stud 24, which is screw threaded into horn 13. A pin 25 normally prevents movement of the stud 24 with respect to the portion 23 of the male die element. The upper end of die element 22 has a reduced portion 27 and a bevel portion 28, which forms the male die surface for countersinking a work piece. For convenience in placing the perforation of a work sheet over the reduced portion 27 of die element 22, its upper end is rounded as shown.

A collar 30 provides a spring pad for supporting the work piece above the die surface at the beginning of an operation and for stripping the work from the die after a formation has been made. For resiliently supporting the collar 30 in its illustrated position, a coil spring 32 seats at

its lower end in a cup-shaped member 33 which has screw threaded connection with male die element and rests upon a plate 34 which in turn rests upon a hexagonal wrench enlargement 35 formed on die element 22. The enlargement 35 seats against the upper face of horn 13.

An inverted cup-shaped member 38, which may be formed integrally with collar 30, is disposed over the upper end of spring 32 and has an outwardly directed flange 39 at its lower end. Screws pass freely downwardly through flange 39 and thread into collar 34 and the proportions of the screws, the cup-shaped member 38 and the spring 32 are such as to provide a predetermined desired initial tension in spring 32 when the parts are in their rest positions, as illustrated in Fig. 4.

The upper female die element is designated 43 and has a hexagonal formation 42 and a reduced upward extension 44, which is retained in a chuck element 45 by means of a set screw 46. The chuck element 45 has a reduced upper portion 47 provided with a stud 48 which is screw threaded into a holder 49, and the stud 48 is pinned to chuck element 45 as at 50. The holder 49 has a flange 51 at its upper end, and the flange 51 co-operates with an inwardly flanged collar 52, which is held to the lower end of ram 16 by means of screws 53. The flange 51 and the flange of collar 52 retain the upper die against ram 16, but, as illustrated in Fig. 4, sufficient lateral clearance is provided to permit shifting of the axis of the female die by loosening the screws 53. The female die may thus be accurately registered with the lower male die. The bottom face of female die element 43 has a beveled recess 55 which comprises the female die surface and an extension recess 56 for receiving the reduced portion 27 of male die element 22 which thus serves further as a guide or leader pin.

Both the female die element 43 and the collar 30 associated with male die element 22 have annular recesses designated 56 and 57, respectively, and collars designated 58 and 59 respectively are pressed over the female die element 43 and collar 30 and thus co-operate to form annular heating passages about the die elements. The collar 58 has a lateral spout portion 60 for receiving a flame or other heat stream from a jet 61. The collar 59 has a similar spout formation 63 for receiving flame from a jet 64. The spout 63 is larger vertically than spout 60 because it moves vertically during operation in a manner which will presently appear, while the jet 64 is relatively fixed with respect to horn 13 during normal operation. The collars 58 and 59 have openings as at 65 and 66, respectively, which serve as discharge passages and permit a continuous flow of hot gases in passages 56 and 57. The openings 65 and 66 may be multiplied about collars 58 and 59 as desired to insure sufficient capacity and distribution of the discharge flow.

The manner in which reciprocation of the piston 18 in cylinder 17 is effected, and with it the ram 16 and upper die means 15, will now be described. In this connection reference will be had particularly to Figs. 2 and 3 wherein the numeral 70 designates a conduit leading from a source of fluid pressure, for example compressed air. The conduit 70 may include a standard air filter and a standard lubricator, these elements being designated 71 and 72 respectively in Figs. 2 and 3. The conduit 70 extends to one port of a four-way solenoid operated valve 73 which is a commercially available unit and accordingly need not be described in detail.

As indicated fragmentarily in Fig. 2, conduit 70 is in permanent communication with a port 74 of valve 73. In the idle position of the machine, port 74 is connected with port 75 which has a fixed conduit connection 76 with the lower portion of cylinder 17, whereby the piston 18 is held in its elevated position. In Fig. 2, the exhaust port of the four-way valve 73 is designated 78 and, likewise in the idle position of the machine, port 78 is connected with port 79 which is permanently connected with the upper side of cylinder 17 by means of conduits 81, 82, and 83, in order, the conduit 82 including a check valve 86 which permits free fluid flow from cylinder 17 to port 79 but closes against retrograde flow. In the idle position of the machine the upper end of cylinder 17 is thus vented to the atmosphere through exhaust port 78.

In addition to the conduit portion 82, conduits 81 and 83 are connected by two additional alternative conduits 90 and 91. The conduit 90 includes an automatic pressure regulating valve 94 which is available as a standard unit and which, in the present apparatus, is adjusted to permit fluid passage from conduit 81 through conduit 90 to conduit 83 only up to a predetermined pressure, for instance 10 lbs. per square inch. The conduit 91 includes a normally closed solenoid-opened valve 95 having an operating solenoid 96. The valve 95 and the solenoid 96 are available as a unitary commercial unit.

In Fig. 3, conductors 100 and 101 lead from a power source by way of a foot operated treadle switch designated 103 in Fig. 1 and branch conductors 105 and 106 extend to the operating solenoid of four-way valve 73. Other branch conductors 108 and 109 connect the conductors 100 and 101 with solenoid 96 of valve 95, but these conductors extend by way of a time delay device 111, which is a standard commercial unit, one form of which is known in the art as a Square D timer.

When the circuit of conductors 100 and 101 is closed by operation of the treadle switch 103 energization of the operating solenoid of four-way valve 73 is immediate, but energization of the solenoid 96 which opens valve 95 is delayed for a predetermined period depending upon the adjustment of the timer 111. In the present apparatus this adjustment may be for a period of the general order of from two to fifteen seconds.

The operation of the pressure means for reciprocating piston 18 and accordingly effecting operating cycles of the die means will now be described. When treadle switch 103 is closed by the operator of the machine, the solenoid of valve 73 is immediately energized and the port connections of valve 73 are shifted so that pressure inlet port 74 connects with port 79 leading to the upper side of cylinder 17 and port 75, leading from the lower side of cylinder 17, is simultaneously connected with exhaust port 78. The check valve 86 blocks conduit 82 and conduit 91 is still closed by valve 95 but pressure is introduced to the upper end of cylinder 17 by way of conduits 81, 90 and 83, the degree of pressure being automatically limited by regulating valve 94. Under the limited degree of pressure thus afforded, female die 15 lowers to engage the work piece and somewhat compress spring 32 and thus lower collar 30; however, the pressure made available is not enough to compress spring 32 to a degree which will begin the actual dimpling formation.

In this position of the parts collar 30 and female die 43 are engaged resiliently but firmly 75 against opposite faces of the work sheet and

transmit their heat thereto by conduction through an annular zone beginning inwardly at the circle defining the ultimate dimpling formation and extending outwardly therefrom. The setting of the timer 111 is such that valve 95 opens automatically after the work sheet has been heated to the required degree. When valve 95 opens automatically the full pressure of the compressed air source from conduit 70 is conducted to the upper side of cylinder 17, the collar 30 is further depressed against the resistance of spring 32, and the desired dimple is die-formed between the male and female die surfaces 28 and 55. When the switch 103 is opened by removal of the operator's foot, four-way valve 73 returns automatically to its initial position and the piston is raised by pressure through conduit 76, free egress of fluid from the upper end of cylinder 17 being permitted by reason of return conduit portion 82 leading to the exhaust port 78 and the check valve 86 which opens freely to fluid flow in this direction.

In the form of invention shown in Fig. 1, the heating medium comprises an oxy-acetylene arrangement and an oxygen tank 120 and an acetylene tank 121 may be housed in the pedestal 11 of the machine. Conventional gauges and regulating valves are illustrated and an oxygen conduit 122 and an acetylene conduit 123 lead to a standard mixer 124 which has two outlet conduits, 125 and 126, each of which receives a proper mixture of oxygen and acetylene from mixer 124. The conduit 125 leads to jet 61 and a conduit 126 to jet 64, as appears from Fig. 1.

The horn 13 is pivotally mounted on base 12, by means indicated generally at 127 in Fig. 1, for free movement about a vertical axis coincident with the vertical axis of the die means, whereby the horn 13 may be swung about to accommodate under hanging portions of a work piece being operated upon without disturbing the working relationship of the upper and lower die means. It is accordingly desirable to run the conduit 126 up through the axis of pivotal movement of horn 13, as shown in Fig. 1, whereby pivotal movement of horn 13 will not interfere with proper and continuous passage of fuel to jet 64.

Jet 64 extends from a block 130 which is pivotally connected to a pair of arms 131 which are in turn pivoted to horn 13. In this way arms 131 may be adjusted about their pivot on horn 13 to bring the jet 64 closer to or farther from the die means and block 130 may be pivoted upon arms 131 an amount sufficient to retain the correct direction of emission of the flame from jet 64. Upper jet 61 is fixed to a block 135 which is pivoted to arms 136 which have adjustable pin and slot connection with head 13 of frame 10. By this means jet 61 may be adjusted upwardly or downwardly and also toward and away from the female die means and its ultimate direction of emission may also be adjusted by adjustment of block 135 with respect to arms 136.

When dealing with the high tensile aluminum alloys hereinbefore specified die temperatures between 400 and 600 degrees Fahrenheit produce good results, the optimum being probably about 550 degrees F. When dimpling for a one-eighth inch countersunk rivet in sheets between about .015 inch and .032 inch thick the holding period of female die 43 and collar 30, prior to final forming by male die element 22, is of the order of several seconds. Obviously, thicker sheets will require longer holding periods than thinner sheets to provide adequate conductive heating of the

part of the metal which is subject to adequate forming.

What is claimed is:

1. Sheet metal forming apparatus comprising a male die and a coaxial female die element, means supporting said male die and said female die element for relative axial reciprocation toward and away from each other, a sleeve element surrounding the male die and resilient means urging the sleeve element toward the female die element whereby the sleeve element and the female die element engage a work sheet in advance of forming engagement between the male die and the female die element during their relative reciprocation toward each other, means for heating one of said elements for heating work sheets engaged therebetween about the portions to be formed by conduction from said element, means actuatable to move said male die and said female die element relatively toward each other with a force less than the force required for metal forming engagement therebetween against the resistance of the resilient means to move said heated element to heat conducting position, and time delay means actuatable to subsequently move said male die and said female die element to metal forming position.

2. Sheet metal forming apparatus comprising a male die and a coaxial female die element, means supporting said male die and said female die element for relative axial reciprocation toward and away from each other, a sleeve element surrounding the male die and resilient means urging the sleeve element toward the female die element whereby the sleeve element and the female die element engage a work sheet in advance of forming engagement between the male die and the female die element during their relative reciprocation toward each other, means for heating one of said elements for heating work sheets engaged therebetween about the portions to be formed by conduction from said element, means actuatable to move said female die element and said sleeve element relatively toward each other into heat conducting engagement with a work sheet, and time delay means actuatable to subsequently relatively move said male die and said female die element to metal forming position.

3. Sheet metal forming apparatus comprising coaxial male and female die elements, means supporting said elements for relative axial reciprocation toward and away from each other, a sleeve surrounding the male die element and resilient means urging the sleeve toward the female die element whereby the sleeve and the female die element engage a work sheet in advance of forming engagement between the male and female die elements during relative reciprocation of the die elements toward each other, means for heating said female die element and said sleeve for heating work sheets engaged therebetween about the portions to be formed by conduction from said female die element and said sleeve, means actuatable to move said die elements toward each other to such heat conducting position with a force less than the force required for metal forming engagement between said die elements against the resistance of said resilient means, and time delay means actuatable to subsequently move said die elements to metal forming position.

4. Sheet metal forming apparatus comprising coaxial male and female die elements, means supporting said elements for relative axial reciprocation toward and away from each other, a sleeve surrounding the male die element and resilient

means urging the sleeve toward the female die element whereby the sleeve and the female die element engage a work sheet in advance of forming engagement between the male and female die elements during relative reciprocation of the die elements toward each other, means for heating said female die element and said sleeve for heating work sheets about the portions to be formed by conduction from said female die element and said sleeve, means for moving said die elements partially toward each other to move the female die element and said sleeve into heat conducting engagement with a work sheet, and time delay means actuatable to subsequently move said die elements to metal forming position.

5. Sheet metal forming apparatus comprising male and female die elements, means supporting said elements for relative reciprocation toward and away from each other, resilient means surrounding the male die element and cooperating with the female die element to engage resiliently against the work sheet ahead of the male die element during relative reciprocation of the die elements toward each other, means for heating said female die element and said means surrounding the male die element for heating work sheets engaged therebetween adjacent to the portions to be formed by conduction from said female die element and said male die surrounding means, means actuatable to move said die elements toward each other to heat conducting position with a force less than the force required for metal forming engagement between said die elements against the resistance of said resilient means, and time delay means actuatable to subsequently move said die elements to metal forming position.

6. Sheet metal forming apparatus comprising male and female die elements, means supporting said elements for relative reciprocation toward and away from each other, resilient means surrounding the male die element and cooperating with the female die element to engage resiliently against the work sheet ahead of the male die element during relative reciprocation of the die elements toward each other, means for heating said female die element and said means surrounding the male die element for heating work sheets adjacent to the portions to be formed by conduction, means for moving said die elements partially toward each other to move female die element and said resilient means into heat conducting engagement with a work sheet, and time delay means actuatable to subsequently move said die elements to metal forming position.
